WELL PUMPING APPARATUS

Application filed October 11, 1930. Serial No. 398,981.

This invention relates to improvements in pump operating mechanism of oil wells and the like.

It is usual practice in connection with pumping mechanism for oil wells to locate a relief link or connection upon a post or standard adjacent to connection where the pull rod is associated with the power line or rod, for the purpose of holding the pull rod when the latter is disconnected from the power line, in order to support the pumping string in proper relation in the well in an inoperative position. It is also conventional to locate a series of pick-up hooks on such standard for the purpose of cooperating with a hook located on the pull rod to take up slack in the latter when the rod is to be connected to the power line, after, say the repairing of a break in the pull rod. It is the purpose of this invention to provide a safety coupling connection between portions of a pull rod or between a pull rod and its power line connection, and to provide a safety detent construction for association with such safety coupling which will enable first, the safe and efficient disconnection of the pull rod from the power line to hold the pumping string inoperative during an otherwise operation of the power line; second, to permit an efficient take-up of slack in the pull rod or line after the repairing of a break therein, with expediency and safety to operators, and third, to permit of the efficient addition of an extra coupling link in the pull rod for the purpose of permitting the lower end of a reciprocating pumping string to bump the standing valve in the well sufficiently to start a proper functioning of the standing valve, in event the same has become sluggish or the check valve thereof caught for reasons well known in the art, and thus permit of pumping of the oil from the well.

Other objects and advantages of this invention will be apparent during the course of the following detailed description.

In the accompanying drawings, forming a part of this specification, and wherein similar reference characters designate corresponding parts throughout the several views—

Figure 1 is a side elevation of parts of the improved device, showing more particularly the connections in a pull rod or line and the association therewith of a detent mechanism.

Figure 2 is a fragmentary plan view of the details of Figure 1.

Figure 3 is a fragmentary view of the details of Figure 1 showing how the detent mechanism is brought into operative connection with a pull line, and more particularly with a coupling link in the latter in event it is decided to accomplish any of the above outlined objects of this invention.

Figure 4 is an enlarged view, partly in section, showing the cooperative construction and association of the detent member of the detent construction, which corresponds to the conventional relief link, with an enlargement or a part of the coupling link or member, which ordinarily corresponds to a disconnecting hook of conventional construction; the detent member being brought into such operation for the purpose of effecting a disconnection of the power line from the pull rod for reason to be hereinafter mentioned.

Figure 5 is a fragmentary view of details shown in Figure 3, but in the more progressive position.

Figure 6 is a fragmentary elevation of details of Figure 5 in a further progressive position, showing disconnection of the pull line and pumping string from power side of the line.

Figure 7 is a plan view of details shown in Figure 2, with the addition of extra coupling links in the pull rod or line, provided for the purpose of accomplishing the second specific object above outlined, namely, to enable proper take-up of the pull line due to resultant slack therein after the repair of broken parts.

Figure 8 is a sectional view showing the relation in which the improved coupling links or connections are associated with each other and with a pull line or power line.

Figure 9 is a sectional view taken substantially on the line 9—9 of Figure 8.

Figure 10 is a fragmentary view, partly in section, showing the relation in which an

extra coupling link is added to the pull line for the purpose of permitting the pumping string to bump the standing valve in a well, for the purpose of repairing some inoperative condition of the standing valve, in order that a pumping of oil from the well may be successfully continued.

Figure 11 is a rather diagrammatic view showing the relation of the effective lengths 10 of coupling links for the pull line or rod to be hereinafter described.

Figure 12 is a front elevation, partly in section, showing the construction of a novel type of hook or detent member for the detent 15 construction.

In the drawings, wherein for the purpose of illustration are shown preferred and other features of the invention, the letter A may generally designate an oil well, wherein a 20 reciprocating pumping string B is operable; having operative connection at its upper end with a pumping jack C of usual construction, with which a pull rod or line D is associated. The invention is mainly concerned 25 with the pull rod, which for purposes of this invention, may include a section 15 operatively connected at 16 with the connecting rod 17 of the pumping jack C, and also a section 20, leading to the power line; details of the 30 invention generally designated at E in the drawings, being associated between the pull rod or line sections 15 and 20.

As in ordinary construction the pumping string B includes the plunger 25 at the lower 35 end thereof having a traveling or working valve 27 connected therewith. An ordinary standing valve 28 is disposed in the well tubing 30, for well known purposes.

The jack C is of usual construction, including the frame 31 pivoted at 32 upon the stationary frame 33; the connecting rod 17 being pivoted onto the movable frame 31 remote from the pivot 32, and having connection, as above mentioned, at 16, with the portion 15 of the pull rod or line.

Referring to the invention E, it is preferred to provide standards or posts 40 and 41 which reciprocably support a plunger rod 42 at their upper ends. The plunger rod 42 at one end is swivelly or pivotally connected with a hook-shaped connection 43, at 44; the hook end 45 of the connection 43 being adapted for releasable connection to an eye or hook end 45^a of the pull rod section 20 above described, as has been shown in Figure 1 of the drawings. The hook 43 is so positioned that if there is any tendency or slack movement of the adjacent ends of the plunger rod 42 and pull rod section 20, the hook will automatically release its connection with the pull rod 20 and drop to the position shown in Figure 6 of the drawings.

The plunger rod 42 extends in a bearing relation thru the upper end of the post or standard 40, and it is adapted for releasable con-

nexion with the pull rod section 15 by means of a plurality of coupling fittings, the principal one of which is an enlarged head or member designated at 50, which is elongated, at one end 51 being cylindrical shaped and providing a screw threaded socket 52 axially therein for detachable connection of the screw threaded end of the pull rod section 15, as shown at 53 in Figure 8 of the drawings, or for detachably receiving the threaded end 54 of a special coupling rod 55, which may vary in length. The structure of the member 50 is such that from a point intermediate its ends it tapers with a diminishing diameter toward the smaller end where a shoulder 58 is formed. Intermediate its ends the body of the enlarged member 50 is provided with a radially disposed entrance slot 60, of a diameter slightly larger than the head 61 which is formed on the end of the special rod 55, or the head 62 of the plunger rod 42, to permit slipping of the head 61 or 62, as the case may be, into the slot 60 to a position axially of the body of the member 51. The body of the member 50 from the end surface 58 to the entrance slot 60 is radially slotted at 64 to permit the insertion of the rod body 42 or 55; the slot 64 being of such depth that the connecting rod 55 or the plunger rod 42 may come to rest axially in the body 50, as shown in Figure 8; the socket 67 being counterbored in the body beyond the entrance slot 60 to permit the head 61 or 62, as the case may be, to slip therein and prevent an accidental disconnection of the rod thus assembled upon the coupling member 50. Thus, it is quite apparent that the member 50 is coupled in the pull rod length, having screw threaded connection at 53 with the pull rod section 15, and having detachable connection with either the end of the plunger rod 42, or one of the special rod lengths 55, which may be connected by another of the members 50 with the plunger rod 42. It is shown in the drawings that the surface 57 facing in the direction of the pumping jack is disposed in a plane normal to the axis of the pull rod, for cooperative connection thereagainst with a detent head or so-called safety hook-off 70, which is part of a detent construction to be subsequently described.

The detent member 70 comprises an elongated body which is substantially crescent-shaped in cross section, or channel-shaped, having a channel way 71 therethrough from end to end which is of greatest width at the fore end 72, shown in Figure 4 of the drawings; the opposite sides 75 and 76 of the body 70 convexly tapering towards the rear end where the inverted channel-shaped member 70 is provided with a rear facing shoulder or surface 74 in a plane normal to the length of the body 70. The channel 71 as above mentioned, tapers gradually from its fore end to its rear end and it is provided with a reduced way 77, shown in Figure 12, of a size which

will only permit the seating therein of one of the rods 42 or 53 of the pull rod construction. The channel 71 is so shaped that the reduced end of the enlarged coupling body 50 may slip into the large end of the channel 71 of the 5 detent body 70, until the shoulder 74 passes the shoulder 57 of the body 50, and at which time the detent member 70 will drop to receive the pull rod section 15, or one of the connecting rods 55, as the case may be, in the reduced end 77 of the channel of the detent member 70, and the position of the parts will be as illustrated in Figure 5 of the drawings, 10 positioning the shoulder 74 of the detent in counter-facing relation with the end surface 57 of the body 50. The detent 70 is provided with laterally extending attaching ears 80 and 81, to which the ends of rods 82 and 83 are detachably connected, as by nuts 84; the 15 rods 82 and 83 extending divergently away therefrom, and being swivelly connected by suitable eyes to eye-bolts 85, detachably connected on the top of the standard or post 40, at opposite sides of the plunger rod 42, which 20 support the detent 70 in position where the same may be raised or lowered to cooperate in a restraining or free relation with respect to any of the coupling connections associated with the plunger or pull rod sections.

As a further feature of the detent mechanism, there is provided an operating lever 90 pivoted intermediate its ends at 91 upon the fore end of a bracket arm 92 which is connected at 93 on the top of the post 40, 25 and extends toward the pumping jack. The end facing the pumping jack has an expansion spring 94 connected therewith; the lower end of the expansion spring being releasably connected thru an opening of an ear or lug 30 formed on top of the detent member 70, as shown in several views of the drawings. The bracket 92 is provided with an upstanding end 97 having upper and lower downwardly facing hooks 98 and 99, either of 35 which are adapted to receive the end of the operating lever 90 at the opposite side of the pivot 91 from the spring connection with the detent 70. The purpose of these hooks 98 and 99 is obvious, since if the lever 90 is 40 hooked at 98 the detent 70 will be lowered to the position shown in Figure 5 so that the detent will slidably receive the pull rod or line therethrough and permit the slipping of one of the coupling connections or enlargements 50 in the direction of the power line, at the time that the power line is pulling the pumping jack for a lifting of the pumping string; permitting this body 50 to pass the 45 detent, as shown in Figure 5, and upon the movement of the power rod in the direction of the pumping jack for permitting a lowering of the pumping line, the end 57 of the coupling rod which has just passed the detent will come into engagement with the surface 50 of the detent 70, which will hold the pull

line section 15 against any further movement for a lowering of the pumping string, independent of the fact that the power rod is still advancing. The lever 90 is hooked in the lower hook 99 to normally elevate the 70 detent 70 to the position illustrated in Figure 1 and to permit an unobstructed operation of the entire pull rod line and its incidental coupling fittings and connections during a normal well pumping operation. 75

From so much of the invention as has been above described it will be clearly understood that if it is desired to disconnect a particular well pumping equipment from the power line, as is sometimes necessary, and well known to those skilled in the art, the detent 70 will be lowered as above mentioned, to the position shown in Figure 5, and upon the upstroke of the power operating mechanism the coupling enlargement 50 will pass from the position shown in Figure 1 past the now lowered detent 70, to the position shown in Figure 5; it being assumed that the power line is operating in the direction shown by the arrows in Figure 5. Upon movement of the power line in the opposite direction to permit a lowering of the pumping string, the enlargement 50 will come into engagement with the detent 70 and the pull rod 15 will be prevented from further movement in the direction of the pumping jack. The pull rod section 20 is still advancing towards the pumping jack and consequently a slack will result which will permit the connecting hook or member 43, above described, to drop from the position shown in Figure 5 to the position shown in Figure 6, disconnecting the particular pumping equipment of the well from the power line and more particularly the pull rod section 20. Immediately the parts have assumed the position shown in Figure 6, the operator may lower the handle end of the lever 90 to the dotted position shown in Figure 6, hooking the lever handle under the lower hook 99. This will tension the spring 94, since the weight of the pumping line in the well urging the coupling enlargement 50 shown in Figure 6 against the detent 70 will be sufficient to hold the latter in a lowered position, and the spring 94 will be expanded. When it is desired to continue the pumping operation the operator will swing the hook 43 upwardly and when the pull rod section 20 comes into position the hook 43 at its end 45 is swung into the eye 45^a. Upon the back stroke of the power line for pulling the rod section 20 away from the pumping jack, it is quite apparent that there will be a release of the weight of the pumping string upon the detent 70, thru the member 50, permitting the spring 94 to draw the detent 70 out of the way to the position shown in Figure 1, and the power line being in operation will cause an operation of the pumping equipment in the well. 130

By reason of breakage of the pull rod or line, the power line is sometimes disconnected, and the parts above described release their connection. Due to the nature and length of the pull line section, in some instances, the weight is such that it can not be stretched taut at a single operation, so that the take-up of slack must be gradual, at successive strokes of the operating line. This take-up is ordinarily accomplished by means of a relief link connection. In the present invention, however, I prefer to use special coupling links comprising special rods 55 above described, detachably threaded at their threaded ends, in the relation mentioned, with the coupling body 50. Any number of these special coupling links may be used, as found necessary to effect an initial connection of the plunger rod 42 therewith and with the pull rod section 15. Thus, as shown in Figure 7, two of the special coupling devices are associated between the pull rod section 15 and the plunger rod 42, as well as an extra one of the head enlargements 50; three of the latter being used altogether. The pull rod having been properly coupled, upon the stroke of the power mechanism away from the pumping equipment in the well, the member 50 most remote from the well will ride past the lowered detent 70 to the position shown in Figure 7, and upon continued movement of the power stroke in the direction away from the well the second of the coupling bodies 50 will pass the lowered detent 70; it being understood that the stroke movement of the pull rod or line is greater than the effective length of one of the special coupling links comprising the body 50 and the rod 55, as shown in the lower portion of Figure 11, to permit the passage of one of the link connections. Then, upon movement of the power stroke in the direction of the well, the detent will hold the coupling member 50 which has just passed the same, and permit the disconnection of the power line at the hook 43 above described, and the link including the rod 55 and the free head or body or member 50 connected therewith will be disconnected from that coupling member 50 which is held against the detent, and thus shortening the effective length of the pull rod. Upon the next power stroke in the direction of the well the plunger rod 42 is connected to the member 50 held directly at the detent 70 and other coupling connections placed to permit a further operation of the pumping equipment for taking up slack in the pull line and removal of the desired number of special link couplings until the pull rod is substantially taut and of a length to deliver the proper stroke to the well pumping line.

Under normal operation of the pumping line, of course, the plunger cups at the bottom of the sucker rod line do not hit the standing valve. The parts of the standing valve

very often become clogged with sediment, and by slight jarring the standing valve may have the sediment removed so as to permit the further functioning thereof. To permit the pumping equipment to thus jar the standing valve, it is proposed by me to use a special coupling length, comprising one of the heads 50 shown in the upper portion of Figure 11, with a special length of coupling rod 55^a of the same construction as the rod 55 above described; the effective length thereof being shorter than the effective length of one of the coupling rods 55, but sufficient to accomplish the purpose described.

It is preferred that the special hook and coupling parts of this invention be made of malleable iron. From the foregoing it is apparent that an improved and safe coupling connection has been provided, for a safety hook-off of the pumping equipment of particular wells, which may be expeditiously put into operation as desired. The special coupling links and parts enable a safety pick-up arrangement. It is to be noted that the coupling parts permit of an axial connection with each other, along the line of pull.

Various changes in the shape, size, and arrangement of parts may be made to the forms of invention herein shown and described, without departing from the spirit of the invention or the scope of the claims.

I claim:

1. In a safety hook-off mechanism for well pumping and operating equipment the combination of a stationary bracket, a lever pivoted on the bracket, a channel-shaped detent having a downwardly facing channel, means connecting the channel-shaped detent with the operating lever at an end spaced from its pivot, means for holding the lever at the opposite side of the pivot from the detent to support the detent into or out of operating relation with a pull line and means holding the detent against movement of said pull line.

2. In a safety hook-off mechanism for well pumping and operating equipment the combination of a stationary bracket, a lever pivoted on the bracket, a channel-shaped detent having a downwardly facing channel, means connecting the channel-shaped detent with the operating lever at an end spaced from its pivot, means for holding the lever at the opposite side of the pivot from the detent to support the detent into or out of operating relation with a pull line and means holding the detent against movement of said pull line, the means connecting the detent to the operating lever comprising an expandible spring normally contracted.

3. In a well pumping apparatus, a pull rod comprising a plurality of sections, means detachably connecting said sections, said means comprising tapped slotted enlargements on said sections, each of said enlarge-

ments having an abrupt shoulder, and a link
between each two of said sections, said link
being provided with a head on one end and
screw threads on the other, the said head
5 fitting in the slot on one of said enlargements
and the threaded end being screwed into the
tapped opening of the other of said enlargements;
means supporting said sections; and
a safety hook device on the support means,
10 comprising a pivoted lever, a detent suspended
from said pivoted lever for holding one
of said sections when detached from the other
of said sections, said detent comprising a
block having a tapered bore and an abrupt
15 shoulder with which one of said enlargements
is adapted to interlock.
